UNITED STATES PATENT OFFICE.

NATHANIEL BOIS, OF SAN FRANCISCO, CALIFORNIA.

ROLLING WINDOW-SCREEN.

1,113,095.

Specification of Letters Patent.

Patented Oct. 6, 1914.

Application filed December 23, 1913. Serial No. 809,418.

To all whom it may concern:

Be it known that I, NATHANIEL BOIS, a citizen of the United States, and a resident of the city and county of San Francisco, State of California, have invented a new and useful Improvement in Rolling Window-Screens, of which the following is a specification.

My invention relates to rolling window screens wherein a suitable screen is secured to a roller having a pinion thereon and may be operated by raising or lowering the lower sash or may be operated independently of the sash, and the objects of my invention are first, to provide improved means for operating a rolling window screen which may be automatically operated when the lower sash is raised or lowered; second, to provide improved means for disconnecting the screen from the operating means; third, to provide means for operating the screen independently of the window by means of a rack which engages a pinion on the roller; fourth, to provide suitable guideways for the screen and the rack; and fifth, to provide means for connecting or disconnecting the lower end of the screen from the window sill.

I accomplish these several features by means of the device disclosed in the drawings forming a part of the present specification, wherein like characters of reference designate similar parts throughout the said specification and drawings and in which—

Figure 1 is an elevation of a window disclosing my invention secured thereto. Fig. 2 is a vertical sectional view of Fig. 1 disclosing the roller secured to the lower end of the lower sash. Fig. 3 is an enlarged detailed sectional view disclosing the manner in which the screen roller is rotatably secured to the lower end of the lower sash, the manner in which the pinion on the roller is engaged by a stationary rack secured to one side of the window frame, and the means whereby the said pinion is moved from engagement with the said rack. Fig. 4 is a view similar to Fig. 3 but disclosing the pinion removed from engagement with the rack. Fig. 5 is a broken plan view of Fig. 3, disclosing the screen retaining strips secured to the sides of the window frame, the stationary rack and the pinion on the screen roller in engagement therewith. Fig. 6 is a diagrammatic view of the screen removed from the roller disclosing the manner

in which the upper edge of the said screen is secured to the roller and the lower edge to a reinforcing strip adapted to be secured to the window sill. Fig. 7 is a broken sectional view through the upper and lower sashes, disclosing a modified form of the invention wherein the roller is stationary and rotatably mounted on the window frame while the rack is slidably mounted within the retaining strips of the screen and adapted to rotate the roller and wind up the screen independently of either sash. Fig. 8 is a plan view of the roller in engagement with the slidable rack, disclosing the relative positions of the screen retaining strips, the screen having been removed. Fig. 9 is a plan view of the securing strip at the bottom of the screen disclosing the movable rack secured thereto, the manner in which the rack is slidably mounted within one of the screen retaining strips, and the manner in which the screen is engaged by the retaining strips.

Referring to the drawings, the numeral 1 is used to designate the lower end of the lower sash of a window having the brackets 2 secured thereto. One of the brackets 2 is provided with the horizontal slot 3 in which one end of a roller 4, having a longitudinal slot 4', and the pinion 5, is rotatably mounted. The pinion 5 is arranged to mesh with and be operated by a stationary rack 6 secured to one side of the window frame in a manner hereinafter more fully described.

A bifurcated lever 7 is pivotally secured as at 8 to the bracket 2 having the horizontal slot 3 therein, said lever being also provided with a pin 9 which is adapted to engage the apertures 10 and 12 in the said bracket 2. When the pin 9 is in the aperture 10 the lever 7 is secured in the position indicated in Fig. 3, which retains the pinion 5 of the roller 4, which is rotatably mounted within the upper bifurcated portion of the said lever 7, in mesh with the rack 6. The lever 7 may be constructed of spring steel or a similar material so as to impart resiliency thereto and thus retain the pin 9 in either aperture 10 or 12. By moving the lever 7 to the position indicated in Fig. 4 of the drawings, the pinion 5 is disengaged from the stationary rack 6.

The upper end of the screen 14 is bent as at 15 around one leg of an angle 16 and securely clamped thereon by means of the U-

shaped member 17, as illustrated in exaggerated form in Fig. 6 of the drawings. The U-shaped member 17 is then inserted and secured within the longitudinal slot 4' of the roller 4, in this manner the upper end of the screen 14 is secured to the roller. The lower end of the screen 14 is overlapped and secured by means of a binding strip 18 which is in turn secured by means of the securing strip 19.

10 Vertical stationary retaining strips 22 and 23 are secured to the sides of the beads 25 of the window frame, the strips 22 being provided with a channel 24 adapted to receive the rack 6. The securing strip 19 secured to the window sill 30 by means of the pivotal buttons 27 which extend through the slots 29 of the strip 19 are turned transversely to the said slots.

20 The operation is as follows. The roller 4 being rotatably mounted to the lower end of the sash 1 and the lower end of the screen 14 being secured, by means of the buttons 27 and securing strip 19, to the window sill 25 30, as the lower sash 1 is raised it causes the roller 4 and the pinion 5 thereon to move with the said sash 1 and the pinion 5 to roll on the rack 6 and unwind the screen 14 as it travels upward. When the window 30 sash 1 is lowered, the operation is reversed and the pinion 5 is rotated in the opposite direction by the rack 6 and the screen 14 is, consequently, rolled upon the roller 4. If it is desired to raise the window without operating the screen 14, the pinion 5 is disengaged from the rack 6 by moving the pin 9 of the lever 7 into the aperture 12 as indicated in Fig. 4 of the drawings. The securing strip 19 may be released from the 35 window sill 30 by turning the buttons 27 so that they will coincide with the slots 29. The window sash 1 may now be raised or lowered without unwinding or winding the screen 14, the said screen being rolled on 40 the roller 4 and raised or lowered with the 45 said sash 1.

In Figs. 7, 8 and 9 of the drawings, I have illustrated a modified form of the invention wherein the roller 4 is rotatably mounted 50 between the slides of the window frame and the rack 6 is slidably mounted within the channel 24 of one of the screen guides 32. The lower end of the rack 6 is rigidly secured to the securing strip 19. The guides 55 32 are in the form of deep channels, are stationary and extend from the roller 4 to the window sill 30. By releasing the securing strip 19 from the buttons 27 and raising the said securing strip, the rack 6 will also be 60 raised and will thereby rotate the pinion 5 of the roller 4 and wind the screen 14 thereon. The guide strips 32 will engage and retain the edges of the screen 14 and effectively prevent the entrance of flies or other insects. By reversing the movement and

lowering the securing strip 19 the rack 6 will also be lowered and rotate the pinion 5 and the roller 4 in the opposite direction. The screen 14 will then be unwound from the roller 4 as the securing strip 19 moves 70 downward. When the securing strip 19 is secured again to the sill 30 by means of the securing buttons 27 the window will be effectively closed against insects.

I have provided a suitable hood 35 which 75 may be secured in any suitable manner above the roller 4 for the purpose of protecting the said roller from the elements.

It is obvious from the foregoing that I have provided a rolling window screen 80 which may be easily operated by means of a pinion rolling upon a rack, wherein either the rack or the pinion may be stationary. It is also obvious that the window screen 85 may be operated automatically by raising or lowering the window sash, or may be disconnected from the sash and operated independently.

Having thus described my invention what I claim as new and desire to secure by Letters 90 Patent is—

1. In a rolling window screen, the combination of suitable brackets adapted to be secured to the lower end of a window sash; a roller having a pinion on one end thereof 95 and rotatably mounted within the brackets; a screen having the upper end thereof secured to the roller; means for securing the lower edge of the screen to the window sill; suitable retaining strips secured to each side 100 of the window frame and adapted to engage and retain the side edges of the screen; a rack secured to one side of the window frame and arranged to engage the pinion on the roller when the window is raised and 105 lowered and to unwind and wind the screen thereon; and means for disengaging the pinion from the rack.

2. In a rolling window screen, the combination of suitable brackets arranged to be secured to the lower edge of the lower sash of a window, one of the said brackets having a horizontal slot therein; a roller rotatably mounted within the brackets, one end 115 of said roller being mounted within the horizontal slot; a suitable screen secured to the roller; a securing strip secured to the lower edge of the screen; means for securing the said securing strip to a window sill; retaining strips secured to each side of the window frame; a stationary rack secured to one side of the window frame and arranged to engage the pinion on the roller when the window sash is raised and lowered and to 120 unwind and wind the screen thereon; and a bifurcated lever pivotally secured to the bracket with the horizontal slot and adapted to move one end of the roller in the said slot and to disengage the pinion on the 125 roller from the stationary rack. 130

3. In a rolling window screen, the combination of suitable brackets arranged to be secured to the lower edge of the lower sash of a window, one of the said brackets having a horizontal slot therein; a roller rotatably mounted within the brackets; one end of said roller being mounted within the horizontal slot, a suitable screen secured to the roller; a securing strip secured to the lower edge of the screen; means for securing the said securing strip to a window sill; retaining strips secured to each side of the window frame; a stationary rack secured to one side of the window frame and arranged to engage the pinion on the roller when the window sash is raised and lowered and to unwind and wind the screen thereon; a bifurcated lever pivotally secured to the bracket with the horizontal slot and adapted to move one end of the roller in the said slot and to disengage the pinion on the roller from the stationary rack; and means for retaining the said lever and the pinion in engagement with the rack.
4. In a rolling window screen, the combination of suitable brackets arranged to be secured to the lower edge of a window sash, one of the said brackets having a horizontal slot therein; a roller rotatably mounted within the brackets, one end of the said roller being rotatably mounted
- within the horizontal slot; a suitable window screen secured to the roller; a securing strip secured to the bottom of the screen; buttons secured to the window sill and arranged to engage and retain the securing strip; suitable retaining strips secured to each side of a window frame and arranged to engage the edges of the screen; a pinion secured to the end of the roller mounted within the slot in the bracket; a stationary rack secured to one side of the window frame and arranged to engage the pinion on the roller and to rotate the said roller and unwind and wind the screen thereon when the window sash is raised or lowered; a bifurcated lever pivotally mounted upon the bracket having the horizontal slot therein, the bifurcated portion of the said lever being adapted to engage the end of the roller having the pinion thereon and to disengage the said pinion from the rack; and means arranged to retain the said lever in position where the pinion will be disengaged from the rack.

In witness whereof I hereunto set my signature in the presence of two subscribing witnesses.
